(57) **CLAIM**

The ornamental design for a laser hand piece, as shown and described.

DESCRIPTION

FIG. 1 is a front perspective view of a laser hand piece showing our new design;

FIG. 2 is a side elevation view thereof;

FIG. 3 is a front elevation view thereof;

FIG. 4 is a back elevation view thereof;

FIG. 5 is a top plan view thereof; and,

FIG. 6 is a bottom plan view thereof.

The broken lines shown are for illustrative purposes only and form no part of the claim. Where broken lines abut a claimed surface it is understood that those broken lines represent an unclaimed boundary between claimed and unclaimed surfaces. None of the broken lines form any part of the claimed design.
